MACHINE FOR DYEING AND TREATING YARN

Filed July 17, 1929

3 Sheets-Sheet 1

The image contains two technical drawings of a conveyor system, labeled Fig. 1 and Fig. 2.

Fig. 1: This diagram shows a top-down view of a conveyor system. A horizontal conveyor belt 14 is supported by a frame. Above the belt, a series of vertical supports 35 are arranged. Two overhead hooks 10 are suspended from the top of the frame. A motor 16 is mounted on the left side of the frame. A vertical support 22 is positioned on the left side. The frame has a base with wheels. Various components are labeled with numbers: 10, 11, 12, 13, 14, 15, 16, 21, 22, 28, 30, 31, 33, and 35.

Fig. 2: This diagram shows a side view of the conveyor system. The conveyor belt 14 is supported by a frame with vertical supports 35. Two overhead hooks 10 are suspended from the top of the frame. The frame has a base with wheels. Components are labeled with numbers: 10, 11, 12, 21, 30, 31, 33, and 35.

UNITED STATES PATENT OFFICE

JAMES HARRY THOMPSON, OF TRENTON, NEW JERSEY, ASSIGNOR TO WALKER & DAVIS, INC., OF PHILADELPHIA, PENNSYLVANIA, A CORPORATION OF PENNSYLVANIA

MACHINE FOR DYEING AND TREATING YARN

Application filed July 17, 1929. Serial No. 378,926.

My invention relates to two-part rack members of machines for use in dyeing, bleaching or otherwise wet-processing skein yarn, cotton, wool or any fiber material and 5 has more particular reference to equipment for removably fastening together registering side rails of the upper and lower portions of the two-part rack members.

A purpose of my invention is to provide 10 a form of fastening between the registering side rails of the upper and lower parts of composite racks of the character indicated that is inexpensive to manufacture and well adapted to efficiently perform the needs of 15 service.

A further purpose is to mount upwardly extending bolt members upon the rails of the lower portion of a two-part rack to cooperate with locking levers vertically pivot- 20 ed upon the rails of the upper portion, the levers in locking position hooking under downward abutments on the upper ends of the bolts.

A further purpose is to lessen the forwardly presented slope of a movable locking member upon the upper portion of a rack of the character indicated by providing vertical adjustment in a cooperating abutment member upon the upper end of a bolt member 25 carried by the lower part of the rack and engaged during the locking movement by the sloping portion of the locking member.

Further purposes will appear in the specification and in the claims.

35 I have elected to show one form only of my invention selecting a form that is practical and efficient in operation and which well illustrates the principles involved.

40 Figure 1 is a side elevation illustrating a machine for dyeing yarn, a two-part yarn rack of the machine being equipped with fastening members embodying one form of my invention.

45 Figure 2 is a side elevation showing the loaded yarn rack of Figure 1 on a truck.

Figure 3 is a broken perspective of a portion of the structure shown in Figures 1 and 2.

50 Figure 4 is a perspective view of the lower

portion of a rack shown partly loaded and in position upon a truck.

Figure 5 is a side elevation corresponding to a portion of Figure 1 or of Figure 2.

Figure 6 is an enlarged fragmentary top 55 plan view illustrating fastening structure embodying my invention.

Figure 7 is a side elevation of Figure 6 shown partly in vertical central section.

Like numerals refer to like parts in all 60 figures.

Describing in illustration and not in limitation and referring to the drawings:—

My invention refers to a detail of a two-part rack for use with machines for treating 65 fibrous material with a liquor that may be for dyeing, bleaching or for any other processing operation.

In Figure 1, I show a two-part rack 10 made up of upper and lower members 11 and 12 respectively, the composite rack being part of a dyeing machine 13.

The dyeing machine includes a dye vat 14 which may be square or rectangular and contains dye liquor 15 adapted to be continuously 75 circulated by a suitable circulating unit 16.

The upper and lower members of the composite rack are separable and are used as a unit when together and as separate units when apart. The upper member 11 is usually used alternately with each one of two similar lower members 12 of which one only is shown. They are adapted by means of my invention to be interchangeably easily fastened to the upper 80 member 11.

Each lower member 12 includes transverse poles 17 for receiving skeins of yarn or the like and side rails 18 that are notched at 19 to receive the pole ends and that are adapted to register with corresponding downwardly presented side rails 20 of the upper member 11. These side rails 20 are not notched.

In operation one of the lower members 12, loaded with skeins of yarn or the like is in the 95 dye vat, presenting its load to the action of the dyeing liquor while the other lower member on a suitable truck 21 is being unloaded from material, as yarn 22, that has been previously operated upon by the liquor in the ma- 100

chine and is then reloaded with material not yet treated in the vat.

I provide the rails of the lower members 12 with upwardly directed metal members that 5 pass through registering vertical perforations in the side rails of the upper member and that present downwardly directed abutments to be engaged by movable locking members above the rails of the upper rack member.

10 My fastening includes upwardly directed metal members 23 preferably bolt members extending from the lower rails with lower shanks 24 firmly fastened to the lower rail and an upwardly directed extension adapted to pass through perforations 25 of the upper rail and each presenting a vertically adjustable abutment 26 in position to make cooperating engagement with a preferably slightly sloping upwardly directed surface 28 of the hook 15 portion of a pivoted lock lever 27.

20 The lock lever 27 is pivotally mounted at 29 above a bearing plate 30 and is adapted to be swung by hand by a suitable handle 31 into a locking position.

25 The upper end of the bolt 23 is preferably reduced in section at 32 and is threaded to carry the nut members 33 and 34.

The upper nut member 34 is a downwardly directed cap having an upwardly presented 30 taper end 35 for more easy entry into the perforation 25 through the upper rail 20. The nut members 33 and 34 lock together and have an outside diameter permitting them to readily pass the perforation 25 through the 35 upper rail.

40 One material advantage of my invention lies in the adaptation to vertically adjust the downwardly directed abutment 26 presented by the upper end of the bolt 23 for locking engagement by the locking member 28.

I preferably make the hook portion of this locking have an approach at 27 that slightly slopes so as to make entry more easy.

45 In practice the engagement between the movable lock member and the downwardly directed abutment of the bolt should be sufficiently firm to insure tight engagement between the upper and lower rails. Otherwise the material under treatment occasionally becomes caught between the upper and lower 50 portions of the rack.

In practice, the upper rack member frequently so changes its form or dimensions, either by warping or by shrinking, due to the 55 action of the hot liquor in the vat as to alter the relative positions of the movable lock member and abutment. By making the abutment member vertically adjustable I am enabled to secure a wedge action that is much 60 more efficient by reason of being able to materially reduce the slope of the wedge, adjusting the position of the abutment to that needed to secure a firm engagement between the upper and lower portions of the rack.

65 Moreover by the use of a pivoted locking

lever I avoid the need for tapping the locking member to place in order to secure tight engagement. Furthermore, with the hand-operated lever there is little or no straining of or injury to the threads on bolt 23, such as might be the case if hook 28 jammed against nut 33 instead of slipping into position under nut 33. This might occur if nut 33 became loose and slipped down on to bolt 23.

70 I may desirably provide each locking lever 28 with a suitable pin 36 for definitely pinning the locking member in its fastening position.

In view of my invention and disclosure variations and modifications to meet individual whim or particular need will doubtless become 75 evident to others skilled in the art, to obtain all or part of the benefits of my invention without copying the structure shown, and I, therefore, claim all such in so far as they fall 80 within the reasonable spirit and scope of my 85 invention.

Having thus described my invention, what I claim as new and desire to secure by Letters Patent is:

1. In a machine of the character indicated, 90 a two-part rack including upper and lower parts to be used at different times together as a unit and apart as separate units, a lower side rail upon the lower part, an upper side rail upon the upper part vertically perforated and adapted to register with the lower side rail when the parts are together, a bolt 95 fastened to place upon the lower rail having an upwardly extending portion adapted to pass through the perforation when the parts are together, a locking member vertically pivoted upon the upper surface of the upper rail having a hook portion adapted in locking position to span the bolt, and a downwardly directed abutment carried upon the 100 upper portion of the bolt adapted to be engaged by an upwardly directed surface of the hook. 105

2. In a machine of the character indicated, 110 a two-part rack including upper and lower parts to be used at different times together as a unit and apart as separate units, a lower side rail upon the lower part, an upper side rail upon the upper part vertically perforated and adapted to register with the lower side rail when the parts are together, a bolt 115 fastened to place upon the lower rail having an upwardly extending portion adapted to pass through the perforation when the parts are together, a locking member vertically pivoted upon the upper surface of the upper rail having a hook portion adapted in locking position to span the bolt, and a downwardly directed abutment carried upon the upper portion of the bolt adapted to be engaged by an upwardly directed surface of the hook, said abutment comprising a nut member 120 vertically adjustable upon the upper end of the bolt.

3. In a machine of the character indicated,

a two-part rack including upper and lower parts to be used at different times together as a unit and apart as separate units, a lower side rail upon the lower part, an upper side rail upon the upper part vertically perforated and adapted to register with the lower side rail when the parts are together, a bolt fastened to place upon the lower rail having an upwardly extending portion adapted to pass through the perforation when the parts are together, a locking member vertically pivoted upon the upper surface of the upper rail having a hook portion adapted in locking position to span the bolt, and a downwardly directed abutment carried upon the upper portion of the bolt adapted to be engaged by an upwardly directed surface of the hook, said hook having a taper entry surface upon its upper side and the said abutment having a vertical adjustment on the bolt.

4. In a machine of the character indicated, a two-part rack including upper and lower parts to be used at different times together as a unit and apart as separate units, a lower side rail upon the lower part, an upper side rail upon the upper part vertically perforated and adapted to register with the lower side rail when the parts are together, a bolt fastened to place upon the lower rail having an upwardly extending portion adapted to pass through the perforation when the parts are together, a locking member vertically pivoted upon the upper surface of the upper rail having a hook portion adapted in locking position to span the bolt, a downwardly directed abutment carried upon the upper portion of the bolt adapted to be engaged by an upwardly directed surface of the hook and a pin means for fastening the locking member in locking position.

5. In a machine of the character indicated, a two-part rack including upper and lower parts for use together and apart at different times, a lower side rail upon the lower part, an upper side rail upon the upper part having a vertical perforation and adapted to register with the lower side rail, a bolt projecting upwardly from the lower rail and adapted to pass through the perforation and having an upper portion of reduced diameter, a locking member vertically pivoted upon the upper rail having a hook adapted to engage and span the reduced portion of the bolt and a vertically adjustable nut upon the upper end of the bolt presenting a downwardly directed abutment to an upwardly directed surface of the hook.

6. In a machine of the character indicated, a two-part rack including upper and lower parts for use together and apart at different times, a lower side rail upon the lower part, an upper side rail upon the upper part having a vertical perforation and adapted to register with the lower side rail, a bolt projecting

upwardly from the lower rail and adapted to pass through the perforation and having an upper portion of reduced diameter, a locking member vertically pivoted upon the upper rail having a hook adapted to engage and span the reduced portion of the bolt and upper and lower vertically adjustable nuts upon the upper end of the bolt, the lower nut presenting a downwardly directed abutment to an upwardly directed surface of the hook and the upper nut locking with the lower nut and capping the end of the bolt.

7. In a machine of the character indicated, a two-part rack including upper and lower parts to be used at different times as a unit and separately and having upper and lower side rails, an upwardly and downwardly adjustable abutment secured to one of the rails and a horizontally movable face cam of low pitch attached to the other rail to engage the abutment.

8. In a machine of the character indicated, a two-part rack including upper and lower parts having adjoining side rails, an upwardly and downwardly adjustable abutment carried by one of the rails, threaded for adjustment to different positions, a lock nut for the abutment to hold it in position as adjusted and a low pitch cam engaging the abutment, taking advantage of the adjustment of the abutment to reduce the necessary extent of pitch for the cam.

9. In a machine of the character indicated, a two-part rack including upper and lower parts having adjoining side rails, an upwardly and downwardly movable abutment, a support for the abutment from one side rail passing through the other side rail, means for locking the abutment in position after adjustment and a horizontally movable low pitch cam carried by the other rail and engaging the abutment.

JAMES HARRY THOMPSON.
